UNITED STATES PATENT OFFICE.

HERMAN P. BANNINGA, OF MUSKEGON, MICHIGAN.

NOZZLE CONSTRUCTION.

Application filed January 26, 1927. Serial No. 163,738.

This invention relates to a nozzle construction, and more particularly to a nozzle especially designed for use in spraying the ashes in the ashpit of a furnace to settle the 5 dust and render the removing of ashes more sanitary.

Another object of the invention is to provide a device of this character so constructed that the water sprayed from the nozzle will 10 not contact with the grates of the furnace to damage the same.

A still further object of the invention is to provide an adjustable nozzle so constructed that by sliding the movable section 15 of the nozzle longitudinally of the pipe in which it is positioned, the width of the spray may be regulated.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing: 30 Figure 1 is an elevational view illustrating the manner of attaching the nozzle.

Figure 2 is a sectional view through the nozzle.

Figure 3 is a sectional view taken at right 35 angles, to Figure 2.

Figure 4 is a sectional view taken on line 4-4 of Figure 3.

Figure 5 is a perspective view of the adjustable nozzle section.

Referring to the drawing in detail, the 40 reference character 5 designates a furnace which is supplied with the usual hinged door 6 that normally closes the ashpit of the furnace.

As shown by Figure 1, the device includes 45 a pipe 7 that has connection with the pipe 8 that supplies water to the boiler of the furnace, pipe 9 being in communication therewith through the elbow 10. At one 50 end of the pipe 9 is an elbow 11 in which the substantially short pipe 12 extends, the upper end of pipe 12 extending into the elbow 13 to which the pipe 14 is connected in such a way that the pipe 14 may swing 55 in a horizontal plane as the door 6 is opened and closed.

Communicating with pipe 14 is a vertical pipe 15 that has an inwardly extended pipe 16 that connects with the body portion 17 of the nozzle which is substantially T- 60 shaped, the same being provided with external threads 18 whereby the same may be secured into a threaded opening of the door 6.

Fitted within the body portion and held 65 therein by frictional contact with the body portion, is an elongated adjustable member 19 which has an eccentrically formed bore 20 and a diagonally disposed slot 21 communicating therewith, the slot 21 extending 70 along the side of the member 19 so that when the movable member 19 is moved to a position to expose the sides of the slot, water may pass laterally therefrom to 75 spread the spray throughout the entire surface of the ashpit.

It will be seen that by moving the nozzle inwardly so that only the end of the member 19 is exposed, the spray will be directed 80 forwardly and downwardly. In order that inward movement of the member 19 may be restricted, a shoulder 22 is formed within the body portion 17.

Positioned adjacent to the shoulder 22 is 85 a screening member 23 designed to filter the water in its passage through the body portion to prevent foreign matter from collecting in the slot of the member 19 to restrict the flow of water therethrough.

Pipe 16 connects with the body portion 90 17 through the extension 24, as clearly shown by Figure 2, the water through the various pipes and pipe 16 being controlled by means of the valve 25. The reference character 26 indicates a removable plug fitted 95 in one end of the body portion 17 for closing the same, and it will be seen that should it be desired to remove the screening member, the plug 26 may be removed permitting access to the interior of the 100 body portion.

From the foregoing it will be obvious that due to the construction shown and described, water may be directed downwardly and laterally over the ashpit of a furnace to settle 105 the dust therein preparatory to removing the ashes.

I claim:

A nozzle including a body portion having a bore therethrough, an extension having a bore therethrough communicating with the bore in the body portion, a pipe in the 110

extension for feeding fluid to the body portion, a removable plug closing the bore at one end of the body portion, said body portion being counterbored at the other end and forming thereby an internal shoulder at the inner end of the counterbore, a member adjustable longitudinally of the counterbore and held therein by frictional contact with the walls thereof, said adjustable member having a bore and having a slot extending from the outer end of said member and open

at its sides in communication with said bore to establish communication between the bore and the atmosphere, said adjustable member being adapted to be rotated to vary the plane of flow of fluid from the body portion and adjustable longitudinally in the body to control the amount of said slot exposed beyond the body portion. 15

In testimony that I claim the foregoing as 20 my own, I have hereto affixed my signature.

HERMAN P. BANNINGA.
